PUMP

Walter Agustus Shallenberg, Salem, Ohio, assignor to The Deming Company, Salem, Ohio, a corporation of Ohio

Application June 1, 1950, Serial No. 165,553

3 Claims. (Cl. 103—87)

1

This invention relates to a pump adapted to force a continuous even stream of water into a service line without the necessity of employing an external tank. An object of the invention is to provide such a pump in extremely simple, compact, self-contained form which shall contain within it a pressure accumulator to store excess pressure and automatically supply it to the stream being delivered when the pressure applied by the pumping mechanism falls below a predetermined amount.

A further object of the invention is to provide a pressure accumulator in the form of a closed flexible bag housed within the pump casing and containing air under pressure which is available at all times to be externally compressed, with a corresponding increase in its internal pressure, by an excess pressure from the pumping elements and to react to augment the pressure delivered by such elements to the service line.

In carrying out this invention, I provide a self-priming pump having a chamber in its base occupied by the closed inflated air bag, subjected externally to the pumping pressure. The pumping elements are centrally located within the base, leaving a surrounding space which is occupied by the air bag, such space being preferably completely annular and the air bag being doughnut-shaped and substantially filling the space while having a portion of its surface in contact with the water being delivered by the pump. A preferred embodiment of my invention is illustrated in the drawings hereof and is hereinafter more fully described.

In the drawings, Fig. 1 is a vertical section through the complete pump; Fig. 2 is a horizontal section through the air bag and a portion of the pump casing above the pumping elements, as indicated by the offset line 2—2 on Fig. 1; Figs. 3 and 4 are details in vertical section in planes indicated by the correspondingly numbered lines on Fig. 1.

As shown particularly in Fig. 1, 10 indicates the hollow base of the pump having a suction intake passageway 11 and a pressure discharge passageway 12. Mounted on the base 10 is an upper casing 20 carrying a suitable motor not shown but adapted to rotate a depending vertical shaft 21 adapted to drive the pumping mechanism in the base.

More specifically, the base 10 is a hollow casting having a substantially horizontal bottom 14, a vertical cylindrical wall 15 and an annular top portion 16. The open space at the top left by the annular portion 16 is in use closed by a top

plate 17 which by suitable spaced portions 18 carries a horizontal top plate 19 on which the motor casing 20 rests.

The pumping mechanism is centrally mounted in the base and has a vertical driving shaft 30 coupled to the motor shaft 21. This pumping mechanism is preferably of the centrifugal type and in the embodiment shown comprises a two-stage centrifugal pump receiving water from the intake 11 and delivering it under pressure to the discharge passageway 12.

As shown in Fig. 1, the lower pumping element comprises a two-part casing 31 and 32 rigidly mounted on an annular horizontal portion of the base about the vertical exit of the intake passageway 11. Within this casing 31 and 32 is an impeller 33 tight on the shaft 30 and receiving water centrally by a passageway 34 and delivering it through an opening 35 to the upper pumping element. The upper element likewise comprises a rigidly mounted two-part casing 36 and 37 and an impeller 38 within the casing and rigidly mounted on the shaft 30. This upper element receives its water from the first pumping element and delivers it via the passageway 39 to the annular space surrounding the pumping members and thence to the discharge passageway 12.

The pump shaft 30 is drivingly supported by the motor shaft 21. A coupling sleeve 40, which is drivingly secured to the upper end of the pump shaft 30, has a split portion which is clamped to the motor shaft 21 by an internally tapered nut 41, thus rigidly connecting the motor to the impellers. The sleeve 40 passes through an opening in the plate 17, which is provided with a fluid retainer 43 to prevent escape of fluid. The lower end of the shaft 30 is journaled in a bushing 44 mounted in an opening formed in the base 10, which is closed by a plug 45. The specific form of the pumping elements, the drive and the support therefor may be changed without departing from my invention.

It will be seen that a comparatively large annular chamber 46 surrounds the impeller casings within the pump base, such chamber being bounded on the outside by the vertical wall 15 and the top and bottom walls 14 and 16 of the base, except at the intake and discharge where the annular space is vertically reduced by the means defining passageways 11 and 12, as clearly shown in Figs. 3 and 4.

Within the chamber 46 above described I mount the doughnut-shaped flexible air container or bag 50, made of any flexible material which is impervious to both air and the fluid to

be pumped. I find rubber or rubber-like material to be suitable for this purpose although fabric which has been treated to render it impervious may be used. This bag when inflated lies against the vertical wall of the base and against the top and bottom plates thereof, except where it arches over the intake and discharge conduits, as shown in Figs. 4 and 3 respectively. The air bag is provided with a filling nipple 55 having an internal check valve. This nipple is made after the manner of the ordinary filling nipple on an automobile tire inner tube. The nipple extends through the top wall 16 of the base and is clamped by an external nut 56, being thus externally accessible for the charging of the air bag by an ordinary air hose.

I mount in the space outside of the impeller casings a vertical tube 60 which provides an inner wall against which the inner periphery of the air bag bears. There is sufficient passageway through this retainer tube 60 to transmit the pressure about the pump casings to the inner wall of the air bag. For this purpose the drawings show this retainer tube as a woven wire grill, but it may be a solid tube with sufficient perforations or passageways to allow transmission of the water under pressure through the retainer tube to the air bag. The retainer tube is notched at 61 in its lowermost portion where it straddles the suction conduit, and at 62 in its uppermost portion on the opposite side aligning with the entrance to the discharge passageway 12.

The air bag is pumped-up through the nipple 55 to a suitable air pressure, for example, 20 lbs. per square inch. When the pump starts to operate it builds up a pressure within the annular space about the impeller casings within the retainer tube 60. If the pressure exceeds that in the air bag, the inner wall of the air bag is thereby pressed away from the retainer tube, reducing the cubic contents of the bag, so that its internal pressure increases. If the pressure delivered by the pumping elements drops below that in the air bag, the air bag expands by reason of its then internal pressure and thus augments the delivered pressure.

In assembling the pump, the air bag is first placed in the hollow base through the opening in the top of the base, and the filling nipple 55 of the air bag is passed through an opening in the base top 17 and anchored in position by an external nut as shown. Then the tubular retainer is mounted along the inner periphery of the air bag, the pumping elements put in place together with the top plate 17. Then the motor casing is mounted on the support 19 and its shaft is coupled by the sleeve 40 with the pump shaft 30.

I have stated that this pump is adapted to deliver water under an even pressure direct to the service line. In Fig. 1, I have indicated a service line 10 connected with a discharge passageway 12 by a vertical T, 71, and in the upper opening of this T I have mounted a suitable pressure gauge 72 connected by a threaded bushing 73. The removal of this bushing with the gauge opens the upper end of this connection to allow the loading of the pump chamber with water from an external source for originally priming it; thereafter the pump is self-priming. To prevent draining the priming water from the pump, I provide a check valve 75 located in an elbow or a plugged T, 76, connecting the suction line 77 with the suction passageway 11.

It will be seen that my pump with its accumu-

lator is a compact structure. The employment of a complete closed flexible air bag does away with the necessity for employing gaskets or other sealing means about the accumulator. Such a bag may be compressed by forcing a portion inwardly to reduce the cubic content without stretching the indented wall of the bag, as adjacent portions merely bent inwardly to accommodate the changed shape. Moreover, as the wall acted on by pressure is forced inwardly the flexing is not about any fixed axis, and as a result weakening in any region, which might otherwise result, is avoided. The bag therefore has a very long life.

My air tube accumulator in the pump not only eliminates the necessity for an external tank but also the air control means heretofore employed to insure a proper amount of air in such tank. In my pump the air being entirely enclosed in an impervious bag cannot be absorbed by the water.

By making this air bag of doughnut-shape and locating it in the base of the pump, such base need be no higher than is required for the pumping elements with their casings and intake and exit passages, and the lateral dimensions need be no greater than is desirable for making a stable support for the pump. The whole pumping unit may therefore be small enough, if desired, so that it may be mounted in a comparatively small space, for instance the idle space beneath a kitchen sink. The pump is available at all times to force a steady stream of water to the service line merely by the closing of the electric switch controlling the operating motor.

It is also a convenience in my pump, that the pump mechanism can be removed for adjustment from its place without disturbing the air charge inside the tube. Such air charge on the other hand may be regulated to the most desirable pressure from the exterior without disturbing the pumping mechanism.

I claim:

1. In a self-contained water system, a vertically extending cylindrical container closed at its bottom and having a top provided with an axial opening, a vertically extending axially positioned perforate cylinder of substantially the same diameter of said opening positioned within said container and extending from the top to the bottom thereof, an endless closed flexible water and air impervious inflated air bag substantially filling the space between the perforate cylinder and the vertical wall of the container, a centrifugal pump having its axis coextensive with the axis of the container mounted within the cylinder and resting on the bottom of the container, a motor supporting head secured to the upper end of the container and coacting with the perforate cylinder and the pump to clamp them in position within said container, said head forming a closure for said container, a motor mounted on top of said closure, a drive shaft extending through said closure and connecting the pump with the motor, said container and pump having aligned inlet openings and an outlet passageway leading from the interior of the perforate cylinder and extending radially within the container adjacent its top and having an upwardly opening discharge.

2. In a self-contained water system, a vertically extending cylindrical container closed at its bottom and provided with a top wall having an axial circular opening extending therethrough, a perforate walled open ended cylinder of substantially the same diameter as the diameter of said open-

ing mounted within said container and extending from the top to the bottom thereof, a flexible water and air impervious inflated air bag substantially filling the space between the perforate cylinder and the vertical wall of the container, a centrifugal pump having a vertically extending axis coextensive with the axis of the container and having a lower end resting on the bottom of the container, said pump having an upwardly extending drive shaft, a motor supporting head secured to the upper end of the container and coacting with the perforate cylinder and the pump to clamp them in position within said container, said head forming a closure for said container and having an axially positioned opening through which said drive shaft extends, a motor having a downwardly extending drive shaft mounted on top of said closure, a separable driving connection between said motor and said pump shafts, said container and pump having aligned downwardly facing inlet openings, a conduit communicating with said openings and extending outward to the periphery of said container, an outlet passageway within the container leading outwardly from the interior of the perforate cylinder and having an upwardly opening discharge.

3. In a self-contained water system for household use, a vertically extending hollow cylindrical container closed at its bottom and having a top provided with an enlarged central opening, a 30 vertically extending axially positioned perforate hollow sleeve of substantially cross section as that of the opening positioned within said container and extending from the top to the bottom thereof, an endless flexible water and air im- 35 pervious inflated air bag substantially filling the space between the perforate sleeve and the vertical wall of the container, a centrifugal pump

having a vertically extending axis coextensive with the axis of the container and having a lower end resting on the bottom of the container and having an upwardly extending drive shaft, a 5 motor supporting head secured to the upper end of the container and coacting with the perforate cylinder and the pump to clamp them in position within said container, said head forming a closure for said container and having an axially positioned opening through which said drive shaft extends, a liquid seal carried by said head and surrounding said shaft to prevent the escape of water from the container along said shaft, a motor having a vertically extending drive shaft mounted on top of said closure, a separable driving connection between said motor and said pump shaft, said container having a downwardly extending peripheral flange forming a base for said container, a laterally extending inlet passageway adjacent the bottom of said container and leading from the periphery thereof to the pump, and a laterally extending outlet passageway within said container and leading from the interior of the perforate cylinder along the top of the container and having an upwardly opening discharge opening.
